Dec. 1, 1864

A. S. Wedder & A. Murray, of Troy, N.Y.
Cessignors to Potter & Co. of same place.
Letters Patent No. 1184. Dated Jan. 1, 1864.

The schedule referred to in these Letters Patent and making part of the same.

To all whom it may concern:

Be it known that we, A. S. Wedder & Archibald Murray, each of the City of Troy, in the County of Rensselaer, and State of New York, have jointly invented or produced a new and original Design for the Doors or Panels of Cooking Stoves; and we do hereby declare that the following is a full and exact description of the same, reference being had to the annexed Photographic drawing making a part of this Specification.

Our said Design consists of a shield-like rosette, i, arranged upon the center of a check work ground, j, which is formed by the intersections of two series of radial grooves that are curved in opposite directions as shown in the annexed drawing.

2

Des. 1184

What we claim as our joint invention or production and desire to secure by Letters Patent is, the ornamental design herein described and represented in the annexed photographic drawing for the doors or the panels of a stove.
